UNITED STATES PATENT OFFICE.

THEODORE PARKER BROWN, OF WORCESTER, MASSACHUSETTS.

PUPPET-VALVE FOR AUTOMATICALLY-OPERATED MUSICAL INSTRUMENTS.

SPECIFICATION forming part of Letters Patent No. 677,059, dated June 25, 1901.

Application filed November 24, 1900. Serial No. 37,608. (No model.)

To all whom it may concern:

Be it known that I, THEODORE PARKER BROWN, a citizen of the United States of America, residing at No. 9 May street, in the city of Worcester, county of Worcester, State of Massachusetts, have invented certain new and useful Improvements in Puppet-Valves for Automatically-Operated Musical Instruments, of which the following is

10 a specification.

My present invention relates to certain new and useful improvements in pneumatically-operated musical instruments, and more particularly to a new and improved "puppet-valve," especially adapted for use in connection with pneumatically-operated musical instruments of the self-playing type; but I do not wish to be understood as limiting myself specifically to such instruments, as the same

15 may be employed with equal facility and effectiveness in connection with other styles of pneumatically-operated instruments.

The invention has for its prime object to provide an extremely simple, cheap, and durable double-seating puppet-valve of the class described, having improved flexible attaching means arranged in such manner as to admit of a perfectly free and unrestricted up-and-down movement or a movement in a true vertical direction of the valve to and from the valve seat or seats, wherein a perfect seating is insured at all times.

The invention comprises the novel features of construction and arrangements of parts hereinafter described and then more definitely pointed out in the claims.

In the annexed drawings, illustrating the invention, Figure 1 is a sectional view of a portion of a well-known type of pneumatic musical instrument, showing one form of my improved valve applied thereto. Fig. 2 is an end sectional view taken on the line $\alpha\alpha$ of Fig. 1. Figs. 3 and 4 are respectively a sectional and a plan view of the valve shown in Figs. 1 and 2. Figs. 5 and 6 are detail views of slightly-modified forms of valves constructed according to my invention.

The reference-numeral 1 designates the longitudinally-disposed wind-trunk, from

50 which the air is exhausted in the usual manner, and 2 the valve-chamber, superimposed

upon the trunk and having communication therewith by means of the port 3. The said valve-chamber communicates through a port 5 with a power-pneumatic 6, which latter has 55 connected to the movable member thereof of a rod 7, that controls the music pipes, reeds, or other sound-producing devices. In the top of the valve-chamber 2, immediately above the port 3, is an air-inlet 4, opening to the 60 outer atmosphere. Arranged below the wind-trunk 1 is a diaphragm-chamber 8, which communicates with a lateral port 9, leading to a duct 10 of the tracker 11, over which the music-sheet 12 travels in the well-known manner. The said chamber 8 is closed by means of a flexible diaphragm 13, constituting the primary pneumatic and having a centrally-arranged disk 14 attached thereto. Leading from the diaphragm-chamber 8 to the wind-trunk 1 is a small channel or opening 15 to control the operation of exhausting the air from the said trunk during the movement of the perforated music-sheet over the tracker.

Arranged within the valve-chamber 2 and 75 disposed so as to alternately open and close the ports 3 and 4 is my improved puppet-valve, which will now be described. As shown in Figs. 1, 2, 3, and 4, the valve comprises a disk or button 16, of wood, leather, or other 80 light material, faced upon opposite sides with some suitable soft seating material, such as leather, one of said seatings being provided with a flexible extension-flap 17, which constitutes the means by which the valve is supported or held in position, said flap being secured along its extreme edge, as at 18, by means of a narrow strip of glue 19, tacks, or otherwise. It will be understood that the flap is secured only at its rear end and that 90 the valve is thus free to move up and down to alternately open and close the ports 3 and 4 and make a perfectly close "seat" at all times, which is an important consideration in this type of instruments. Secured to the 95 valve block or button and depending centrally therefrom is a rod 20, having adjustably fitted to the lower end thereof, by means of a threaded connection, a head 21, which seats upon the disk 14, attached to the dia- 100 phragm 13 in such manner that when the latter is bulged upward the said rod will be

raised to force the upper face of the valve against the seat of the port 4 to close the latter and open the port 3.

In the modified form of valve illustrated 5 in Fig. 5 I have shown the same as comprising two disks 22 22', secured to opposite sides of a narrow flexible strip or flap 23, said disks being each faced with leather or other suitable seating material. The strip is secured 10 at its rear end only to a block 24, whereby it is raised so as to lie substantially centrally of the upper and lower walls of the valve-chamber.

The form of valve shown in Fig. 6 is substantially the same as that shown in Fig. 1, except that the flexible strip or flap 25 is attached to the upper wall of the valve-chamber and the disk or button 26 is attached to the under side of the strip or flap.

20 In the constructions herein shown and described it will be seen that the puppet-valve is secured to or mounted upon a flexible strip, which latter is attached at its rear end only by a narrow strip of glue or other suitable 25 means, and is not otherwise fastened or confined, thus giving it a perfectly free and unrestricted movement up or down to open or close the ports with nothing to cause it to stick and prevent it from coming to a perfect 30 seat at all times. Furthermore, by mounting the valve upon a strip, as described, it can be easily and quickly secured in place and the construction enables it to be manufactured at a low cost.

35 The method of operation is the same as in all instruments of this class. The wind-trunk 1 being under suction, (or force, if the opposite mechanism is employed,) when an opening or 40 perforation appears in the music-sheet 12 over the duct 10 in the tracker 11 the inrush of air, acting upon the under side of the diaphragm 13, lifts it against the head 21 on the end of the rod 20, thus raising the latter and with it the valve 16, lifting it from its seat 45 over the port 3 to open the latter and closing the port 4, allowing the power-pneumatic 6 to collapse under the influence of the suction (or force) of air in the wind-trunk and causing the rod 7 to operate the speaking 50 device of the musical instrument.

It will be observed that the attached or fixed end of the flap which flexibly holds the valve in place is relatively remote from the valve, and this constitutes an important feature of 55 my invention, for if the edge of the valve were in close proximity to the attached or fixed end of the flap then the latter would operate merely as an ordinary hinge and the valve would not seat accurately and closely to its 60 seats unless one or both faces of the valve were beveled or inclined or unless one or both of the valve-seats were similarly beveled or inclined. By fixing or attaching the flexible flap, however, at a point relatively 65 remote from the valve said flap forms a loose flexible connection which will permit the valve to move in a true vertical direction in-

stead of merely allowing it to oscillate like a hinge, and thus cause the parallel faces of the valve to accurately seat against both its 70 seats or ports.

What I claim, and desire to secure by Letters Patent, is—

1. In a pneumatically-operated musical instrument, the combination with a valve-chamber having oppositely-disposed ports, of a valve having two opposite faces disposed within said chamber and adapted to alternately open and close said ports, and a flexible strip fixed at one end to a stationary support and 80 attached at its other end to the valve, the strip being fixed to its support at a point relatively remote from the valve whereby a relatively long and unconfined portion of said flexible strip intervenes between its attached 85 end and the valve and thus permits the valve to move in a true right line, substantially as described.

2. In a pneumatically-operated musical instrument, the combination with a valve-chamber having oppositely-disposed ports, of a valve having two opposite parallel faces disposed within said chamber and arranged to alternately open and close said ports, and a flexible strip fixed at one end to a stationary support and 90 attached at its other end to the valve, the strip being fixed to its support at a point relatively remote from the valve whereby a relatively long and unconfined portion of said flexible strip intervenes between its attached 95 end and the valve and thus permits the valve to move in a true right line, substantially as described.

3. In a pneumatically-operated musical instrument, the combination with a valve-chamber having oppositely-disposed ports, of a valve having two opposite faces disposed within said chamber and arranged to alternately open and close said ports, and a flexible strip fixed at one end to a stationary support arranged in a plane intermediate the plane of 105 said ports and at its other end attached to the valve intermediate the opposite faces of the latter, substantially as described.

4. In a pneumatically-operated musical instrument, the combination with a valve-chamber having oppositely-disposed ports, of a valve having two opposite faces disposed within said chamber and arranged to alternately open and close said ports, and a flexible strip 115 fixed at one end to a stationary support and at its other end to the valve, said valve comprising two disks attached to the opposite sides of the free end of the strip at a point relatively removed from the fixed end of the 120 strip, substantially as described and for the purpose specified.

Signed by me at Worcester, Massachusetts, this 20th day of November, 1900.

THEODORE PARKER BROWN.
